DESIGN FOR AN AUTOMOBILE

Gordon Miller Buehrig, Auburn, Ind., assignor, by
mesne assignments, to Auburn Automobile
Company, Auburn, Ind., a corporation of
Indiana

Application August 5, 1935, Serial No. 57,946

Term of patent 7 years

To all whom it may concern:

Be it known that I, Gordon Miller Buehrig, a citizen of the United States, residing at Auburn, in the county of De Kalb and State of Indiana, have invented a new, original, and ornamental Design for an Automobile, of which the following is a specification, reference being had to the accompanying drawings, forming a part thereof.

Fig. 1 of the drawings is a top plan view of an automobile, showing my new design and illustrating the oval-shaped casing elements of the

collapsible headlights flush with the fenders, that is, in the position in which they are disposed when the headlights are in their inoperative or collapsed position. Fig. 2 is a side elevation. Fig. 3 is a front elevation. Fig. 4 is a rear elevation. Fig. 5 is a perspective of a portion of the front end of the automobile.

I claim:

The ornamental design for an automobile, substantially as shown and described.

GORDON MILLER BUEHRIG.
